Des. 191,096
Patented Aug. 15, 1961

191,096

CHILD'S MUSICAL TOOTH BRUSH OR SIMILAR ARTICLE

Ralph S. Gordon, 138-05 Cronston Ave., Belle Harbor,
N.Y., and Irving Kandell, 35-24 78th St., Jackson
Heights, N.Y.

Filed July 25, 1960, Ser. No. 61,508

Term of patent 14 years

(Cl. D9—2)

FIG. 1

FIG. 2

FIG. 3

FIG. 4

FIG. 1 is a front perspective view of a child's musical tooth brush or similar article, showing our new design.

FIG. 2 is a rear elevational view thereof.

FIG. 3 is a side elevational view thereof.

FIG. 4 is a top plan view thereof.

The dominant feature of the design resides in the portion shown in full lines.

We claim:

The ornamental design for a child's musical tooth brush or similar article, substantially as shown and described.
